FOLDING RACK FOR DOLL CLOTHES OR SIMILAR ARTICLE

Warren C. Bertleson, 1417 Vista Ave.,
Boise, Idaho 83705

Filed Nov. 30, 1972, Ser. No. 311,049

Term of patent 14 years

Int. Cl. D6—99

U.S. Cl. D6—6

FIG. 2

FIG. 1 is a top perspective view of a folding rack for doll clothes or similar article embodying my new design.

FIG. 2 is a bottom perspective view from the side opposite the FIG. 1.

I claim:

The ornamental design for a folding rack for doll clothes or similar article, substantially as shown.
